TRIMMING MECHANISM FOR GRINDER WHEELS

Robert W. Dickeson, Detroit, Mich., assignor to
The Gear Grinding Machine Company, Ham-
tramck, Mich., a corporation of Michigan

Application April 3, 1944, Serial No. 529,314

4 Claims. (Cl. 125—11)

1

The invention relates to mechanisms of that type designed for use in fashioning grinder wheels for form grinding.

It is the object of the invention to obtain a simple construction of mechanism for mounting on the work carrying table of the grinding machine which is particularly adapted for the trimming of long radius arcuate curves.

It is a further object of the invention to provide means for accurately determining the length of the arcs and for forming the same in tangent relation to other curves.

Still further it is an object to obtain a construction which can be compactly arranged on its mounting and which is much smaller in dimensions than the radii of certain of the curves trimmed thereby. With these objects in view the invention consists in the construction and method of operation of the trimming mechanism as hereinafter described in the drawings.

In the drawings:

Fig. 1 is a side elevation of the trimming mechanism associated with the work holder for the work to be ground;

Fig. 2 is a central longitudinal section partly in elevation through a portion of the trimming mechanism;

Fig. 3 is a cross section substantially on line 3—3, Fig. 2, also showing portions in elevation;

Fig. 4 is a plan view of the mechanism shown in Fig. 3;

Fig. 5 is a section on line 5—5, Fig. 4;

Fig. 6 is a section on line 6—6, Fig. 5;

Fig. 7 is a plan view similar to Fig. 4 illustrating the means for angular adjustment;

Fig. 8 is a longitudinal section of another portion of the trimming mechanism;

Fig. 9 is a cross section on line 9—9, Fig. 8 showing portions in elevation;

Fig. 9A is an elevation of a portion of the construction shown in Fig. 9.

Fig. 10 is a diagrammatic elevation illustrating a specific construction of work which may be ground by the trimmed grinder wheel; and

Fig. 11 is a diagram illustrating a geometrical principle involved in the construction of the trimming mechanism.

In the present state of the art various trimming mechanisms have been constructed for the trimming of arcuate and straight line curves in tangent relation to each other. Usually the arcuate curves are of relatively short radius so that the centers thereof can be located within a frame of small dimensions. For trimming arcuate curves of large radius or for non-arcuate curves,

a trimming mechanism may be employed including a preformed templet and a pantograph mechanism. This, however, greatly increases the complexity and cost of the apparatus. With the trimming mechanism forming the subject matter of the instant invention I am able to trim relatively long arcuate curves without extending the supporting frame to commensurate dimensions. The geometrical principle involved in the construction is diagrammatically illustrated in Fig. 11 as follows.

Geometry.

In a plane 1, 2, 3, 4 is a coincident plane 1, 5, 6, 4 having a small radius circle 7 drawn therein. If the latter plane is swung about an axis 8—8 into a position which is oblique in its relation to the plane 1, 2, 3, 4, the circle 7 or rather the projection thereof into the original plane becomes an ellipse. While no part of an elliptical curve is a true arc of a circle, a small portion of the curve on opposite sides of the center of the major axis very closely approximates a true arc. Thus, if a small arc 9—9 is drawn from a center 10 with the radius much greater than that of the circle 7, it will be found to almost exactly coincide with a portion of the ellipse. In fact, the difference between this arc and the elliptical curve is of the order of .00002 of an inch. Such a minute error is well within the tolerance limits for many grinding operations. Making use of this principle I have constructed a trimming mechanism in which the trimming point is moved through an arcuate curve of relatively small radius in a plane which is oblique to an axial plane of the grinder wheel. This will trim in the cross sectional contour of said wheel a curve which is approximately an arc of much longer radius. Consequently, the supporting frame of the trimming mechanism may be of dimensions smaller than the radius of a curve trimmed thereby while, at the same time, said trimming point will travel about a fixed axis in said frame.

Specific structure to be ground.

The trimming mechanism may be used for fashioning grinder wheels to grind various types of work but I have illustrated in Fig. 10 one structure for which it is adapted. This is a wheel-like member 'a' having an axis 'b' and a plurality of tooth-like portions 'c, c', c'', c''' projecting from its peripheral surface. These projections are not gear teeth of involute or cycloidal contour but, on the contrary, are formed with arcuate curved opposite sides 'd, d' connected by small fillets 'e, e' to the peripheral curve 'f' concentric with the axis

b. The surfaces to be ground are d , d' , e , e' and f tangent to each other and the radius of each of the arcuate curves d , d' is greater than the radius of the curve f . Another characteristic of the structure is that the projections are in pairs, the members of each pair being at a predetermined angle or circular pitch in relation to each other, while the angle between successive pairs is greater. It is unnecessary to explain the utility of this structure for that forms no part of the instant invention.

Grinding machine

As illustrated in Fig. 1, the grinding machine is provided with the usual reciprocating work table A having mounted thereon head and tail stocks B and C carrying the work supporting center D and D'. E represents the work on an arbor E' engaging the centers D and D' and F is the grinder wheel. G is the trimmer mounted on the table A in rear of the tail stock C and comprising a mechanism G' for trimming the opposite sides of the grinder wheel and a mechanism G² for trimming the periphery of the grinder wheel.

Side trimming mechanism

The grinder wheel is trimmed to a cross sectional contour corresponding to the interdental contour of the work and as above stated the side portions are long radius arcuate curves. H is a frame mounted on the table which is formed with oppositely inclined faces H', H² on opposite sides of the axial plane of the work. Between the portions H', H² is a horizontal face H³ for locating and supporting a gauge rest I secured by bolts I'. This gauge member has at opposite ends thereof V-shaped cradles I² for receiving like cylindrical portions I³ of a gauge I⁴. The latter is used in setting the trimming points to cylindrical surface I⁵ as will be hereinafter explained. Mounted on the inclined faces H', H² are members J each of which is adjusted to a predetermined angle about an axis J' normal to the surface on which the member is mounted. The member J carries a tapered bearing J² for receiving a correspondingly tapered shank K' of a diamond carrying member K. A raw-hide seal J³ between J and K' excludes all grit or other foreign matter from the working parts. At the opposite end of the shank K' is a threaded portion J⁴ having nuts J⁵ and a washer J⁶ thereon for drawing the tapered shank in close engagement with the bearing J². A hollow cap J⁷ secured to the member J encloses these nuts and washer. At the inner end of the member K' is mounted an arm K² for carrying the diamond K³ and holder K⁴ therefor which latter may be adjusted by a screw K⁵ and locked by a screw K⁶. The distance between the diamond point and the axis of the member K is relatively short in comparison with the radius of the curve which is to be trimmed by said point in the cross sectional contour of the grinder wheel. However, because of the angular adjustment of the members J on the inclined surfaces H' and H² about the axes J', the path of said point is in a plane at an oblique angle to the plane of rotation of the grinder wheel. This will form in the contour trimmed an elliptical curve approximately corresponding to an arcuate curve of the desired radius.

It is necessary that the trimmed curve should be not only of the proper radius but also of a definite arcuate length. This, together with means for oscillating the arm K², is preferably accomplished by the following construction. L is a piston

member extending axially of the frame H with its opposite ends in engagement with cylinders L' and L² in said frame. Between these cylinders the frame H is hollow and within this space is a cross member L³ centrally secured to the piston L. The opposite end portions of the member L³ are inclined into substantial parallelism to the surfaces H' and H² and are slotted for engagement with the spherical projection K⁷ at the free end of a rock arm K⁸ secured to the shank K'. The slotting is at approximately the same angle at which shank K' is finally located in member J on said inclined faces H' and H². The arrangement is such that an axial movement of the piston L will, through the members L³ and K⁸, impart a rocking movement to the shank K' and a corresponding angular movement to the arm K². However, the amount of angular movement of the arm K² is determined by the length of axial movement of the piston L which is limited by stops at opposite ends thereof in the cylinders L' and L². The piston L is guided in its axial movement by a pin L⁴ extending upward from the central portion thereof and carrying a member L⁵ which engages opposite parallel sides of a slot H⁴ in the surface H³. This will permit axial movement of the piston but will prevent any angular movement thereof.

Mechanism for trimming the root curve

To complete the fashioning of the grinder wheel, the peripheral surface thereof must be trimmed to an arcuate curve of a predetermined radius from the axis b. This curve f must terminate at opposite ends in tangent fillet curves e, e' which latter are also tangent to the curves d and d' trimmed by the mechanism G'. The trimming mechanism G² which accomplishes this result is of the following construction. M is a bifurcated frame mounted on the table A in rear of the frame H. N is a shaft extending axially in alignment with the centers D and D' having its opposite ends journaled in the furcations of the frame M preferably by taper roller bearings M' and M². Caps M³ and M⁴ enclose the opposite ends of the shaft and the bearings in said furcations. Upon the portion of the shaft N extending intermediate the furcations is mounted a housing N' which is keyed to the shaft and forms an upwardly extending arm. Journaled in the upper portion of this housing arm is a shaft O which is mounted preferably in roller bearings O', O² and has its axis parallel to the axis of the shaft N. The furcation M⁵ of the frame M is hollow and is adjacent to the housing N' with a sealing ring M⁶ therebetween to exclude the entrance of dust or dirt. On the portion of the shaft N within the hollow furcation M⁵ is secured a member P which has oppositely extending arms P'. P² are adjustable screws engaging the arms P' and extending over stops P³, being locked by nuts P⁴, so that by adjusting the screws the amount of rocking movement permitted to the shaft N is accurately determined. There is also revolvably mounted on the shaft N adjacent to the member P a downwardly extending rock arm Q. The hub Q' of this rock arm extends into the housing N' and is secured to an upwardly extending arm R having a gear segment at its upper end which intermeshes with a pinion R' secured to the shaft O. The downwardly extending arm Q has at its lower end a cylindrical portion Q² which engages a piston S in a transversely extending cylinder S' mounted in the lower portion of the frame M. The cylinder S' is cut away at S² in its central

portion a sufficient amount to permit the passage of the rock arm Q and the movement of the piston S. The opposite ends of the cylinder S' are closed by caps S³ and hydraulic fluid is admitted through these caps to actuate the piston as hereinafter described. However, the stroke of the piston is limited by adjustable screws S⁴ engaging the caps S³ and forming stops for contacting lugs S⁵ on the ends of the piston. The housing N' (Figs. 8 and 9) has a partition N² therein which is adjacent to the arm R. In this partition is a transversely extending channel N³ for receiving slidable blocks N⁴ and a spring N⁵ between these blocks. The arm R has a pair of spaced pins R² projecting therefrom into the channel N³ and blocks N⁴ which latter have shoulders N⁶ pressed against the pins by the spring N⁵. The blocks are also sufficiently cut away at N⁷ opposite the shoulders N⁶ to permit independent movement of the pins under certain conditions. N⁸ are adjusting screws engaging the housing N' and extending into the channel N³ at opposite ends thereof, said screws limiting the outward sliding movements of the blocks N⁴ in the channel. They are used to set the blocks N⁴ so there will be no play between said screws and blocks and/or no play between the blocks and pins R², as end play would result in an undesirable movement of diamond T².

With the construction as thus far described, it will be understood that movement of the piston S in the cylinder S' will rock the arm Q and the arm R connected thereto. Movement of the arm R will be communicated to the housing N' through the medium of the pins R², blocks N⁴ and spring N⁵. This spring is sufficiently pre-loaded to normally hold the shoulders N⁶ of the blocks in contact with the pins R² so that the housing N' will rock with the arm R. However, as the housing N' is keyed to the shaft N and the latter is keyed to the member P having the oppositely extending arms P' and screws P², rocking movement of the housing is limited by contact of the screws P' with the stops P³. Thus, by adjusting the screws P² the length of arcuate movement of the housing N' and shaft O carried thereby is accurately determined. When the housing N' is at the limit of its movement, the arm R is still free to rock inasmuch as this arm is not positively connected to either the housing or the shaft N. Thus, continued movement of the arm R will cause one of the pins R² to move the block N⁴ in the channel N³ against the resistance of the spring N⁵. Such independent movement of the arm R will cause the gear segment thereon to communicate rotary movement to the pinion R' and through the latter to rotate the shaft O. The shaft O has connected to one end thereof the trimmer arm T which carries at its outer end the diamond holder T' and diamond T². The latter is offset from the axis of the shaft O so as to trace a curve concentric with this axis. The radius of this curve may be changed by adjusting the diamond holder T' in the arm T so that a proper curve may be selected to form the fillets e, e' connecting the root curve f with the side curves d, d'.

Briefly summarizing the operation above described, the housing N' and arm R will travel together and without communicating any rotary movement to the shaft O until the screw P² engages the stop P³. This trims the portion of the grinder wheel corresponding to the root curve f. Further movement of the arm R rotates the shaft O and causes the diamond T² to trim the curve

corresponding to the fillets e or e'. This fillet curve is exactly tangent to the root curve f and by properly adjusting the screws P² it will also be tangent to the side curve d or d'. The rotation of the shaft O is limited by the adjusting screw S⁴ which when contacting with the lug S⁵ prevents further movement of the piston S.

Operating mechanism

10

The trimming mechanisms G' and G² are hydraulically operated and the operation of each is controlled by a valve. The detailed construction of this hydraulic operating mechanism is not illustrated but, in general, the frame H has mounted on its front face a fixture U including a pair of adjacent hydraulic valves U¹ and U². These valves are adjusted by handles U³ and U⁴ and the hydraulic connections (not shown) are such that the handle U³ controls the operation of the side trimmers while the handle U⁴ controls the operation of the root and fillet trimmer. Before operating the side trimmers the table A is adjusted into a position in relation to the grinder wheel indicated by F', Fig. 1. The handle U³ is then moved to a position which will admit hydraulic fluid to the cylinder at the left end of the piston L to move said piston to the right. This through the member L³ and rock arms K⁶ will simultaneously rotate the shafts K' swinging the arms K² and diamond points K³ downward. When the handle U³ is returned to its original position, the piston L will be actuated in the reverse direction swinging the arms K² and diamond points K³ upward. After completion of the side trimming operation, the table is adjusted to a position relative to the grinder wheel illustrated at F², Fig. 1. This will bring the diamond point T² into the vertical axial plane of the grinder wheel after which the handle U⁴ is operated to actuate the piston S. This, as above fully described, will trim the root curve and also the tangent fillet curves at opposite ends of said root curve.

45

To set the diamond points K³ the gauge member I⁴ has its cylindrical portions I³ placed in the V-shaped cradles I² after which each diamond holder K⁴ is adjusted by the screw K⁵ into contact with the cylindrical surface I⁵. It is then locked in this position by the screw K⁶. This will place the diamond points K³ at exact radial distance from the axis of the gauge member I⁴ which will properly position them for trimming the grinder wheel.

What I claim as my invention is:

1. A trimmer mechanism for grinder wheels comprising a rock shaft, a rock arm revoluble therewith, a shaft parallel to said rock shaft mounted at the outer end of said rock arm, a trimmer point mounted on the latter shaft at a predetermined distance from the axis thereof, a second rock arm independently revolvably mounted on said rock shaft, resilient yieldable means coupling said rock arms, a connection between said second rock arm and the shaft carrying said trimmer point whereby said shaft will be rotated by independent rocking movement of said second rock arm, a stop for limiting the angular movement of said first mentioned rock arm, a stop for limiting the movement of said second rock arm positioned to permit movement of the latter after arrest of movement of said first rock arm, whereby said trimming point will first trace a curve about the axis of said first mentioned shaft and will then trace a short radius curve

50

65

70

75

tangent to the first curve about the axis of said second mentioned shaft.

2. A trimming mechanism for a grinder wheel, comprising a frame having a pair of supporting surfaces at opposite oblique angles to the plane of rotation of said grinder wheel and on opposite sides thereof, a rock shaft mounted on each of said surfaces with its axis parallel thereto and extending at an oblique angle to the line of intersection between said surfaces and the plane of rotation of the grinder wheel, rock arms connected to said rock shafts, trimmer points carried by said rock arms, a cradle on said frame centrally between said oblique surfaces adapted to receive a cylindrical member seated in said cradle forming a gauge for setting said diamond points, and means for rocking said rock shaft to cause said trimmer points to trace arcuate curves in the trimmed surfaces on opposite sides of said grinder wheel.

3. In a trimming mechanism, a pair of coaxial rock arms, a resiliently yieldable connection between said rock arms for normally moving the one with the other, a shaft carried at the outer end of one of said rock arms, a trimmer point mounted on said shaft, a connection between said shaft and the other rock arm for causing rotation of said shaft upon relative movement of said rock arms, actuating means for the last mentioned rock arm, and stops for limiting the rocking movement of said first mentioned rock arm whereby said trimmer point will trace a long radius curve while said rock arms move together and will trace a short radius tangent curve by the independent movement of the second rock arm.

4. In a trimming mechanism, a rock shaft, a housing fixedly mounted on said rock shaft and extending radially therefrom, a second shaft journaled at the outer end of said housing parallel to said rock shaft, a trimmer point carried by said second shaft a predetermined distance from the axis thereof, a rock arm rotatively mounted on said first mentioned shaft extending radially within said housing, a gear segment at the outer end of said rock arm, an intermeshing gear segment on said second shaft, yieldable connecting means between said rock arm and housing for normally causing the same to move together, means for rocking said rock arm through a predetermined angle of movement, and adjustable stops for limiting the rocking movement of said housing to less than that permitted to said rock arm whereby said trimmer point will trace a long radius arcuate curve during the rocking of said housing and short radius tangent curves at opposite ends of said long radius curve during the independent movement of said rock arm.
